PACKING CUP RETAINER

Steve Schnell, Overland, Mo., assignor to Wagner
Electric Corporation, St. Louis, Mo., a corpora-
tion of Delaware

Application December 16, 1939, Serial No. 309,571

1 Claim. (Cl. 309—34)

My invention relates to packing cups for pistons and more particularly to means for retaining the cup on the piston.

One of the objects of my invention is to provide an improved means for retaining a packing cup in proper position on the head of a piston.

Another object of my invention is to provide a readily attachable and detachable retaining means for an annular type of piston packing cup which will at all times hold the cup in engagement with the head of the piston and also cause the cup to have such pressure engagement with the surfaces it contacts that fluid cannot pass the cup in either direction.

Other objects of my invention will become apparent from the following description taken in connection with the accompanying drawing in which Figure 1 is a cross-sectional view of a cylinder and piston having associated therewith a packing cup and retainer embodying my invention; and Figures 2 and 3 are views showing the packing cup and retainer as detached from the piston.

Referring to the drawing in detail, numeral 1 indicates a cylinder having associated therewith a piston 2 which can be either actuated by the piston rod 3 if it is desired to produce fluid pressure or which can actuate said rod if fluid under pressure is supplied to the cylinder ahead of the piston. The forward face 4 of the piston is provided with a central projection 5 upon which is mounted an annular packing cup 6 of yieldable material such as rubber or the like. As shown, the radial thickness of the packing cup is such that it fits between the projection and the cylinder wall and the rear surface of the cup is flat to engage the face 4 of the piston. The forward face of the cup is provided with an annular groove 7 which forms an outer lip portion 8 engaging the cylinder wall and an inner lip portion 9 engaging the surface of the projection 5.

The forward end of the piston projection has an annular shoulder 10 which is at a slightly greater distance from the face of the piston than the axial thickness of the cup. On the shoulder 10 there is also provided a second annular shoulder 11.

In order to maintain the cup in proper position on the projection and insure that the cup will have pressure engagement with the cylinder wall, the piston face and the surface of the projection there is provided my special retainer 12. The body 13 of the retainer is of annular form and of U-shaped radial cross section so as to fit into

the groove 7 of the cup. The inner portion of the body carries axially extending fingers 14 and the ends are adapted to engage shoulder 11 when the retainer is in operative position. The length of these fingers is such in relation to the cup and other parts that when engaging the shoulder they will cause the body portion 13 to apply an axial compressing force on the cup at the groove 7 and in a direction toward the face of the piston. This force will insure that the cup will at all times be held in engagement with the face of the piston during relative movement between the piston and cylinder. Also this force will cause the cup, due to its yieldability, to "flow" in such directions as to engage the cylinder wall and the surface of the projection with considerable pressure which will be sufficient to seal fluid in the chamber ahead of the piston or prevent it from entering the chamber by passing the piston.

The retainer and cup can be very easily mounted on the piston as the cup need only be mounted on the projection by stretching it sufficiently to get it over the shoulders and then the retainer pressed into position. The fingers 14 are resilient and will snap into position behind the shoulder 11. To remove the retainer, the fingers need only be sprung out from behind the shoulder. By the use of the retainer the cup will be prevented from having any relative movement with respect to the piston, thus insuring that the sharp inner sealing corner on the inner lip 9 will not be damaged by butting against the shoulder 10 as would be the case if the retainer were not used. Also the fingers 14 hold the lip 9 against the surface of the projection and assist in the sealing at this point. It is also to be noted that the outer portion of the U-shaped body of the retainer is so shaped in relation to the adjacent surface of groove 7 of the cup that a portion of the inner surface of lip 8 will be exposed to fluid pressure whereby said pressure can apply a force assisting in maintaining the lip in engagement with the cylinder wall. If the cup should swell because of the fluid used, the retainer will only cause the cup to engage the surfaces it contacts with a greater pressure, thus increasing the sealing action.

Being aware of the possibility of modifications in the particular structure herein described without departing from the fundamental principles of my invention, I do not intend that its scope be limited except as set forth by the appended claim.

Having fully described my invention, what I

claim as new and desire to secure by Letters Patent of the United States is:

In fluid pressure apparatus, a cylinder, a piston provided with a projection having a shoulder spaced from the piston face, an annular sealing cup of yieldable material positioned on the projection and having an annular groove in its forward face forming inner and outer lips for engagement with the cylinder wall and the surface of the projection, respectively, and a retainer for preventing the cup from having relative movement with respect to the piston and the projection, said retainer comprising a member constructed of a single piece of thin metal and having an annular portion of U-shaped radial cross-section for engaging the base of the groove by its outer curved surface and integral axially extending fingers overlying and engaging the sur-

5 face of the inner lip to firmly hold it in contact with the surface of the projection and having their ends engaging the shoulder, said fingers being laterally flexible with respect to the annular portion to permit their being passed over the shoulder and to a position behind the shoulder when the retainer is placed in operative position and to facilitate their disengagement from the shoulder when the retainer is to be removed and said fingers also being of such length that when positioned behind the shoulder they will cause the annular portion to apply an axial pressure to the cup by means of the annular portion of U-shaped radial cross-section to thereby force the cup into pressure engagement with the piston face, the projection and the cylinder wall without cutting the material thereof.

10 15 STEVE SCHNELL.
